ATTORNEY.

UNITED STATES PATENT OFFICE.

JOHN W. BELLAIRS, OF MISHAWAKA, INDIANA.

FABRIC-ROLL-END PROTECTOR.

Application filed December 17, 1923. Serial No. 681,239.

To all whom it may concern:

Be it known that I, JOHN W. BELLAIRS, a citizen of the United States, residing at Mishawaka, in the county of St. Joseph and 5 State of Indiana, have invented certain new and useful Improvements in Fabric-Roll-End Protectors, of which the following is a specification.

The invention relates to fabric roll end 10 protectors, and had for its object to provide adequate protection for the ends of fabric rolls to prevent damage to the edges of the fabric due to rough handling, and in the shipment thereof by careless loading 15 and unloading which permits the rolls to fall and strike on edge with resultant damage to the edge of the fabric. A further object is to provide a closure for the ends of the rolls which are rolled in tubular form, 20 whereby nails, glue, and other securing material for applying the fabric, as in the case of roofing material, may be carried within the roll and the loss thereof prevented during shipment or in the handling thereof by 25 the dealer and the ultimate consumer.

A further object of the invention resides in the provision of end closures for rolls of fabric, such as for rolled roofing material, which closures may be handily and quickly 30 applied and as readily removed, and which closures and means for securing same are simple in structure, are of few parts, and may be cheaply manufactured.

A further object is to provide a clamp 35 linked to the end of a rod adapted to be passed through the fabric roll for connecting the closure caps, whereby the clamp may be used, after being partially passed through an aperture in the caps, as a means for holding 40 and guiding the rod end through such aperture in the placement of the caps to position against the ends of the fabric roll.

With the above and other objects in view, the invention resides in the combination and 45 arrangement of parts as hereinafter set forth, shown in the drawing, described and claimed, it being understood that changes in the precise embodiment of the invention may be made within the scope of what is 50 claimed without departing from the spirit of the invention.

In the drawing:

Figure 1 is a longitudinal sectional view of one end of a fabric roll and closure cap 55 for the end thereof with the securing means

therefor, as taken on the line 1—1 of Fig. 2, the dotted lines showing the manner of applying and securing the cap to place.

Figure 2 is an end view showing the cap as applied and secured to the end of the 60 fabric roll.

Figure 3 is a fragmentary view, partly in section, showing the cap connecting rod, closure cap and clamping member in operative position.

Referring to the drawing, the numeral 1 designates a roll of fabric or other material having a hollow portion or central opening 2 extending the length thereof, one end of such a roll only being shown and considered necessary for the purposes of making a clear and full disclosure of the invention. In actual practice an end cap 3 is applied to each end of the fabric roll. Each end cap is provided with a central projecting portion 4 fitting into the hollow center 2 of the roll, and a flat body or flange portion 5 fitting against the end of the roll so as to cover and protect the edges of the fabric against damage in the shipment and handling of the 70 same. The projecting or dished portion 4 of the cap is adapted to snugly fit within the hollow portion of the roll in order to prevent lateral displacement thereof with respect to the roll.

The end caps 3 are held against endwise displacement by a rod 6 connecting the end caps which passes through the hollow portion of the roll, and the present improvement relates more particularly to the means 90 employed for effecting the attachment between the ends of the rod and the caps and for exerting a pull on the caps in the direction of each other, whereby the caps will be firmly held against the ends of the roll. 95 It will be obvious that for all practical purposes one end of the rod 6 may be connected with one of the end caps 3 in any suitable manner, and that a pull exerted on the rod through means bearing on the other end 100 cap will tend to draw said caps in the direction of each other, hence a single means only for effecting such drawing action is shown and described, although, if preferred, like means may be employed at both ends 105 of the roll. To one end of the rod is linked a clamping member 7, which preferably consists of a sheet metal stamping having an elongated slot 8 disposed to one side of the longitudinal center line thereof, and 110

2
having its ends 9 rounded as shown. The end of the rod 6 passes through the slot 8 and is bent parallel with the rod portion 10, whereby the clamping member is held 5 on edge with respect to the rod end and remains free to be shifted with relation to the rod end within the limits of the slot 8, as in the manner shown by dotted lines in Fig. 1. As shown in Fig. 2, the end cap 10 3 is provided with a central circular perforation 11, through which the clamping member will pass endwise, as shown by dotted lines in Fig. 1, and from which it will be seen that by partially passing the 15 clamping member through said perforation and then gripping the end of the clamping member with the fingers, the cap may be applied to place on the end of the roll and the clamping member made to serve as 20 a means for guiding the end of the rod through said perforation, which greatly facilitates the assembly of the parts in their operative relation. To effect the clamping action the free end of the clamping member 25 is forced toward the end cap, which produces a camming action between the rod and the end cap, thereby imparting a pull or draw upon the rod and a bearing pressure upon the end cap, with the result that both 30 caps will be drawn into firm contact with the ends of the roll.

After being moved to clamping position, the clamping member 7 may be shifted endwise so as to be fully disposed within the 35 dished portion of the cap and to bear fully along its longitudinal edge upon the end plate, thereby protecting the clamping member against injurious distortion should the roll be dropped on end with violence, and 40 by having a long bearing contact with the cap the pressure on the cap is distributed, thus permitting relatively thin sheet metal to be used for the caps without danger of the same buckling too much under pressure or the breaking thereof. With the rod, 45 end cap, and clamping member in operative position, as shown in Fig. 3, the bent over end of the rod reenters the perforation 11 in the end cap, with the result that the 50 edge of the perforation closely encompasses such hook-shaped portion, and prevents a straightening out of such hook portion under a pull exerted thereon in the operation of the clamping member 7 which it otherwise 55 could not resist, and especially so if the roll should be subjected to a violent endwise impact by being dropped from an elevation, whereby a smaller gage wire will effectively serve as a rod than would otherwise permit and with a resultant material 60 saving in the quantitative production of the rods.

It will be seen that my device is simple and efficient for its purposes, and that the

same may be easily and quickly applied to 65 or removed from a roll.

What is claimed is:—

1. The combination with a roll having a central opening therethrough, of end caps 70 adapted to engage the ends of the roll, a connection between said end caps including a rod extending through the roll and the end caps, and a cam member cooperating with one end of said rod and one of the ends caps for exerting a pull on the rod and 75 a bearing pressure on said cap.

2. The combination with a roll having a central opening therethrough, of end caps 80 adapted to engage the ends of the roll, means for connecting said end caps including a rod extending through the roll and the end caps, a bar linked with one end of said rod having a slot disposed longitudinal of and to one side of the longitudinal axis thereof through which the rod end is looped, said bar when folded against the cap exerting a pull on the rod and a bearing pressure against the cap.

3. The combination with a roll having a central opening therethrough, of end caps 90 adapted to engage the ends of the roll, means connecting said end caps extending through the roll, and means having a camming action cooperating with one end of said cap 95 connecting means to effect a pull on both end caps in the direction of each other.

4. The combination with a roll having a central opening therethrough, of end caps 100 adapted to engage the ends of the roll, means connecting said end caps including a rod extending through the roll, one of the caps having a central aperture, a bar having a slot therein disposed longitudinally of and to one side of the longitudinal axis of the 105 bar and through which one end of said rod is hooked, said bar being adapted to pass endwise through said aperture in the cap and foldable and shiftable with respect to the rod end to bear lengthwise against the cap.

5. The combination with a roll having a central opening therethrough, of cap members 115 adapted to engage the ends of the roll, a rod having connection at one end with one of said cap members and extending through the roll with its other end projecting through an aperture in the other cap member, said projected end of the rod being bent upon itself to form a hook the free end of which reenters said aperture, and a clamping member connected with said hooked end of the rod adapted to pass through said aperture and operative to effect a bearing pressure on the cap member and a pull on the rod.

In testimony whereof I affix my signature.

JOHN W. BELLAIRS.
